DESIGN FOR A BLUEPRINT DRYING MACHINE

Richard G. Beck, Adrian, Mich.

Application October 1, 1945, Serial No. 122,433

Term of patent 14 years

(Cl. D61—1)

To all whom it may concern:

Be it known that I, Richard G. Beck, a citizen of the United States, and resident of Adrian, in the county of Lenawee and State of Michigan, have invented a new, original, and ornamental Design for a Blueprint Drying Machine, of which the following is a specification, reference being had to the accompanying drawing, forming a part thereof.

The drawing is a perspective front elevation of

a blueprint drying machine showing my new design.

Both sides of the machine are substantially the same in appearance, and the rear side is plain.

The dominant features of the design are shown in full lines.

I claim:

The ornamental design for a blueprint drying machine, substantially as shown and described.

RICHARD G. BECK.
